STORAGE RACK FOR WINE BOTTLES OR THE LIKE

Eugene J. Majewski, 121 Elmore St.,
Park Ridge, Ill. 60068

Filed Sept. 2, 1970, Ser. No. 24,809

Term of patent 14 years

Int. Cl. D7—99

U.S. Cl. D44—29

FIG. 1

FIG. 2

FIG. 3

FIG. 4

FIG. 1 is a top plan view of a storage rack for wine bottles or the like showing my new design.

FIG. 2 is a front elevation view;

FIG. 3 is a slightly reduced scale side elevation view; and

FIG. 4 is a perspective view.

I claim:

The ornamental design for a storage rack for wine bottles or the like, as shown.
